UNITED STATES PATENT OFFICE.

CLARENCE T. MAPES, OF CRAFTON, PENNSYLVANIA.

UNDERREAMER.

No. 904,344.

Specification of Letters Patent.

Patented Nov. 17, 1908.

Application filed January 28, 1908. Serial No. 413,013.

To all whom it may concern:

Be it known that I, CLARENCE T. MAPES, a citizen of the United States of America, residing at Crafton, in the county of Allegheny and State of Pennsylvania, have invented certain new and useful Improvements in Underreamers, of which the following is a specification, reference being had therein to the accompanying drawing.

10 This invention relates to underreamers, for reaming out or enlarging well-holes, and particularly to such devices intended for underreaming—that is, reaming out or enlarging the well-hole drilled below a casing, 15 in order to permit the casing to be lowered farther down.

The object of my invention is to provide a simple, inexpensive and durable underreamer that can be successfully operated in 20 the most indurate strata of an oil field.

There are certain localities in this and foreign countries, where the operation of drilling oil, gas or Artesian wells is carried on, where broken and cavy strata of rock must 25 be drilled through, and these formations are encountered at various depths. When such a formation is reached in the usual method of drilling, further attempt to drill the hole deeper in the usual way is useless, due to 30 the caving in of rock and other substances around the drilling tools, thus retarding the action of said tools. A line of screwed casing or pipe must then be put into the well to afford protection for the tools in the further effort to complete the well to the required depth; this can only be accomplished 35 by the alternate use of the drilling tools and an underreamer operating through said line of casing or pipe.

40 An underreamer comprises a body, adapted to be attached to the drill stem, and carrying one or more bits or dogs having cutting edges, said bits or dogs adapted to be compressed to the nominal diameter of the 45 reamer-body and to automatically expand as they are passed down through and out of the bottom section of the line of casing or pipe and present a cutting surface of sufficient diameter to permit of the casing being lowered as the operation of underreaming 50 proceeds.

55 My invention aims to provide an underreamer wherein positive and reliable means are employed for effecting a movement of the dogs or reamer heads, and bracing and firmly holding said dogs or reamer heads

while the underreamer is in operation. To this end I have devised an underreamer having laterally moving dogs or reamer cutters which are placed in an operative position by 60 a spreader head or wedge block moved between said dogs or reamer heads, this spreader head firmly bracing the dogs and receiving any strain to which the dogs may be subjected when reaming.

65 Further, I aim to provide an underreamer consisting of comparatively few parts that can be easily and quickly assembled, easily manipulated to enter a well casing and easily disassembled when the dogs or reamer heads need sharpening. Parts of the underreamer are arranged whereby they will be protected while passing through a well casing, and are of such construction as to be easily renewed when completely worn.

70 My invention will be presently described in detail and then specifically pointed out in the appended claims.

75 In the drawings: Figure 1 is a front elevation of my reamer illustrating the spring- 80 case thereof in section and the reamer in position to enter the casing of a well, Fig. 2 is a side elevation of the reamer, illustrating the dogs thereof in an operative position, Fig. 3 is a horizontal sectional view taken 85 on the line $\alpha-\alpha$ of Fig. 1, Fig. 4 is a similar view taken on the line $\gamma-\gamma$ of Fig. 2, Fig. 4^a is a bottom plan view of the spreader head detached. Fig. 4^b is a vertical sectional view 90 of a part of the spreader head showing in dotted lines a portion of the dogs or reamer-bits in extended position. Fig. 4^c is a detached perspective view of the resilient strip carried by the spreader head for normally retaining the dogs or reamer-bits in engagement therewith. Fig. 5 is a longitudinal sectional view of a reamer taken on the line 95 $a-a$ of Fig. 2, Fig. 6 is a front elevation of a reamer, partly in section, illustrating the reamer as shown in Fig. 1 in position to 100 enter the casing of a well, Fig. 7 is a similar view of a reamer, illustrating the manner of placing the dogs in position to enter the casing of a well, Fig. 8 is a side elevation of the spreader head or wedge block used in connection with the underreamer, Fig. 9 is a front elevation of the same, Fig. 10 is a side elevation of one of the dogs of the underreamer, Fig. 11 is a plan of the same, and Fig. 12 is a front elevation of the dog.

105 To put my invention into practice, I provide a reamer-body 1, having at its upper

end a screw joint 2 for a sub or spring-case 3, said spring-case having a central longitudinal bore 4. This sub or spring-case is provided at its upper end with a screw joint, 5 (not shown) similar to the screw joint 2, and in conjunction with the reamer-body is used in connection with a drill stem or jars (not shown), thus constituting part of the string of oil and Artesian well drilling tools. The 10 reamer-body 1 is cylindrical and contiguous to the screw joint 2 is provided with oppositely disposed flat faces 5, adapted to receive a wrench, (not shown) commonly in use to tighten and loosen the screw joint 2.

15 Longitudinally of the reamer-body 1 a bore 6 is formed, the lower end of said bore terminating in a cylindrical recess 7, for the reception of a spreader head or wedge block 8, detachably mounted upon the lower end of 20 a rod 9, that extends upwardly through the bore 6 into the bore 4 of the spring-case 3. The upper end of the rod 9 is provided with a nut 10, and encircling said rod 9, within the bore 4, are two coil springs 11 and 12, 25 with an interposed washer 13 between said springs. The proclivity of these springs is to normally maintain the spreader head or wedge block 8 within the recess 7 of a reamer-body, and I use two springs instead 30 of one, due to the fact that greater resiliency and a longer period of use can be obtained from two springs than from one long spring.

The lower end of the reamer-body is provided with two alining dove-tail grooves 14 35 for the dove-tail tongues 15, carried by the upper flat ends of two oppositely disposed dogs, that are laterally moved and maintained in an extended position through the medium of the spring actuated spreader 40 head or wedge block 8. The confronting faces of the dogs are tapered, as at 16, and provided with dove-tail tongues 17, these tongues being approximately half the length of the tapered faces of said dogs. The confronting faces of the dogs are also provided 45 with central semi-cylindrical grooves 18 cutting away a portion of the tapered faces and the tongues 17 of said dogs. The grooves 18 provide a central opening to clear 50 the rod 9, when said dogs are retracted or drawn towards one another in the grooves 14. The outer faces of the dogs are rounded as at 19 with the upper end thereof beveled, as at 20; the sides of said dogs are flattened, 55 as at 21, and the lower ends of the dogs are beveled, as at 23, to provide cutting edges and clearance for the dogs when operating in a well.

The spreader head or wedge block 8 is of 60 a peculiar shape,—appearing in side elevation as a cone, and in front elevation as an inverted T. The spreader head has its sides beveled as at 24, and provided with dove-tail grooves 25 to receive the dove-tail 65 tongues 17 of the dogs, thus establishing an

adjustable connection between said dogs or bits and spreader head. In addition to the dove tail grooves 25 on the sides of the spreader head, the latter is provided on the bottom with a transversely-extending dove-tail groove 26 which communicates or intersects at its ends with the lower ends of grooves 25. This groove 26 receives a plate, spring or resilient strip 27 of a length substantially equal to the length of the groove 70 26, so that the end portions of said strip normally close the lower ends of the grooves 25 as shown in Fig. 5, and the strip is in engagement with the lower ends of the tongues 17. The said strip is provided intermediate its ends with dovetail tongues 26^a which hold the strip in the groove 26, the strip being thus held only at its central portion, so that the end portions thereof may be depressed as the spreader head is drawn 80 upwardly, as clearly illustrated in Fig. 4^b. This plate spring or resilient strip 27 is employed for normally holding the dogs in engagement with the reamer-body 1 and prevent any loose vertical movement of the dogs 85 with relation to the reamer-body, which might be incurred by the tongues 15 wearing within the grooves 14. This plate spring or resilient strip forms an important factor of 90 my invention, as it prevents pounding of the dogs, when the underreamer is in operation. The dogs are limited in their inward movement by contacting, as shown in Fig. 3 of the drawings.

By reason of the plate or resilient strip 100 27 being secured to the spreader block only at the central portion of such plate or strip, and the ends thereof being therefore free to be depressed, it will be observed that should any wear of the tongues 15 occur, which is 105 extremely likely, owing to the rough usage to which devices of this nature are subjected, that all lost motion that would otherwise be occasioned due to such wear, will be taken up by reason of the ends of the plate 110 or strip 27 pressing upwardly against the dogs or bits. The object of securing the plate or strip 27 at the center only and thus leaving the ends thereof free to be depressed, is to prevent the strip or plate from acting 115 as a positive stop to further upward movement of the spreader block 8. If the strip were held at its ends as well as at the center thereof, it will be observed that as soon as the strip came in engagement with the lower ends 120 of the tongues 17 of the dogs or bits, it would act as a stop to prevent further upward movement of the spreader-head. Since however, the strip or plate is resilient, due to the ends thereof being free from connection 125 with the spreader-head, the said ends will be depressed as the spreader head is drawn upward into the recess 7 to further spread the dogs or bits, while at the same time, the said depressed ends of the strip by their en- 130

gagement with the lower ends of the tongues 17 of the dogs or bits, are pressing upwardly on the latter, and are thus effectively holding the latter to prevent any lost motion between the tongues 15 of the dogs or bits and the groove 14 in the body 1 that receives said tongues 15. The spreader head is provided with a central bore 28 terminating in a threaded socket 29 adapted to receive the threaded end 30 of the rod 9. The curved lower sides 31 of the spreader head have their bottom edges beveled, as at 31^a, whereby the spreader head will easily enter the upper end of the casing, as will hereinafter appear.

The reamer-body is formed with diametrically opposed recesses 35, said recesses being formed in the sides of the reamer-body that are at right angles to the sides having the grooves 14 formed therein. The recesses 35 are formed with beveled shoulders 36, and adapted to normally lie in said recesses are diametrically opposed resilient arms or trip bars 37, having their lower ends reduced, as at 38, to loosely fit in sockets 39 provided therefor in the spreader head 8. The upper ends of the resilient arms or trip bars 37 are provided with enlargements 40 adapted to protrude from the sides of the reamer-body, when the dogs are expanded or in an operative position, but lie flush with the reamer-body when the dogs are retracted and the spreader head lowered between said dogs.

In order to insert the underreamer or tool in the casing of a well the dogs are drawn inwardly by virtue of the vertical movement of the spreader head or wedge block having dove-tail shaped grooves to receive the tongues of said dogs. To pull the spreader head 8 downwardly, I use two hook-shaped members 33, loosely connected to the derrick floor, as at 34. These hook-shaped members are adapted to engage in angularly disposed recesses 32 provided therefor in the curved lower sides 31 of the spreader head. These hook-shaped members 33 are employed for holding the spreader head 8, while the reamer-body is elevated to place the springs 11 and 12 under tension. When the spreader head 8 is pulled downwardly by using the hook-shaped members 33, the resilient arms or trip bars 37 are carried downwardly in the recesses 35 until the upper ends of said arms engage the shoulders 36, this movement being limited by the dogs contacting, as shown in Fig. 3. It is now necessary to temporarily hold the spreader head in this position, due to the springs 11 and 12 being compressed and under tension. To accomplish this, I use a ring 41, which is split or made open at one side, as shown in Figs. 1, 5 and 6. This ring can be readily slipped into place at the flat faces 5 of the reamer-body. The underreamer or tool is then in condition to

be lowered into the well. As the underreamer passes into the casing, the ring 41 impinges the upper end of the casing and is released from engagement with the resilient arms 37. These arms are now held by the casing, and the ring 41 is removed, and the tool is further lowered. The tool can now be lowered into the casing and will pass through it without the dogs contacting with its interior. The enlargements 40 of the resilient arms have their ends rounded so as to enter the casing readily and pass any slight obstructions it may meet as the tool is lowered through the casing. These rounded ends also permit of the tool being easily drawn upward through the casing. As the underreamer is lowered, the dogs, through the action of the interior walls of the casing holding the resilient arms from outward movement and thus holding the rod 9 from upward movement, will be held out of contact with the casing, avoiding wear on the dogs and injury to the casing. As soon as the enlargements 40 of the resilient arms pass below the lower end of the casing, which is elevated a short distance from the shoulder of the small hole to be reamed, these resilient arms will be forced upwardly in the recesses 35 by virtue of the spreader head 8 moving upwardly between the dogs, caused by the expansion of the springs 11 and 12. The dogs are then expanded or in position for operation, as illustrated in Fig. 2 of the drawings.

I now desire to call attention to the fact that the spreader head braces the dogs when in action, and by extending upwardly into the reamer-body, adds rigidity to the entire tool. By interposing the spreader head, it is impossible for the dogs to recede should an indurate obstacle be encountered in the hole that is being reamed. The upper ends of the dogs occupy approximately the area of the end of the reamer-body, consequently these dogs will be prevented from collapsing, and in action will be as durable as if they were formed integral with the reamer-body. This is an important feature of my invention and insures stability of the dogs. As the underreamer or tool is raised and allowed to fall, as in the usual operation of reaming the hole of a well, the lower outer edges 23 of the dogs will strike upon the shoulder left below the lower end of the casing and cut it away, thus enlarging or reaming out the hole previously drilled to the size desired. In raising and lowering the underreamer, the force of impact drives the dogs downwardly, this force being sustained by the reamer-body 1, which provides a substantial backing and prevents the force of impact being in any other lines than vertical. As the hole is reamed, the casing can be lowered. In withdrawing the underreamer, the upward movement of the same, causes

the enlargements 40 of the resilient arms or trip bars 37 to impinge the lower end of the casing, holding the arms or bars 37, the spreader head 8 and the rod 9, while the upward movement of the reamer-body places the springs 11 and 12 under tension. This movement of the underreamer contracts or draws the dogs inwardly, and immediately upon the shoulders 36 of the recesses 35 registering with the upper ends of the arms or bars 37, these arms recede, enter the casing and are held against the shoulders 36 by the interior wall of the casing. The tool then can be completely withdrawn from the casing.

The underreamer in its entirety is made of strong and durable material, such as steel, and on account of the compact arrangement of the various elements, it is impossible for the reamed material to interfere with the operation of withdrawing the underreamer from a well.

It is thought that my invention will be fully understood from the foregoing description taken in connection with the drawings, particularly by those skilled in handling underreamers.

I reserve the right to make such changes in the size, proportion and minor details as are permissible by the appended claims.

Having now described my invention what I claim as new, is:—

1. In an underreamer, the combination with a spring-case, of a reamer-body carried thereby and having a bore formed therein, said reamer-body having its lower end provided with diametrically opposed dove-tail grooves, dogs, tongues carried by said dogs and adapted to fit in said grooves, tongues carried by the confronting faces of said dogs, a spring held rod mounted in the bore of said reamer-body and extending into said spring-case, a spreader head secured to the lower end of said rod and having grooves formed therein to receive the tongues of said dogs, a resilient plate spring or strip carried by the lower end of said spreader head and adapted to impinge the lower ends of the tongues carried by said dogs, and resilient arms or trip bars loosely connected to said spreader head and extending upwardly in the sides of said reamer-body for temporarily holding said spreader head in a lowered position during the passage of said underreamer through the casing.

2. In an underreamer, the combination of a reamer-body having diametrically opposed recesses formed therein, with oppositely disposed grooves at its lower end, dogs mounted for lateral movement in said grooves, tongues carried by the confronting faces of said dogs, a spring held rod mounted in said reamer-body, a spreader head fixed upon the lower end of said rod, and having grooves to

receive the tongues of said dogs, a resilient strip carried by the lower end of said head for impinging the lower ends of the tongues of said dogs, and means for temporarily holding said spreader head in a lowered position during the passage of a tool through the casing.

3. In an underreamer, the combination of a reamer-body having its lower end provided with diametrically opposed dove-tail grooves, dogs movably mounted in said grooves, tongues carried by the confronting faces of said dogs, a spring pressed rod supported by said reamer-body, a spreader head carried by the lower end of said rod and having grooves formed therein to receive the tongues of said dog, and means carried by said spreader head and engaging diametrically opposed sides of said reamer-body for holding said dogs out of engagement with a casing when passing therethrough.

4. In an underreamer, the combination of a reamer-body, laterally movable confronting dogs arranged at the lower end of said body, a spring pressed rod supported by said body, a spreader head carried by the lower end of said rod and slidably connected to said dogs for expanding and retracting the same, and means carried by said spreader head and engaging in the sides of said body for holding said dogs in a retracted position during the passage of said underreamer through a casing.

5. In an underreamer, the combination of a reamer-body, diametrically opposed movable dogs connected to the lower end thereof, a spreader head movably supported from said reamer-body and slidably connected to said dogs for expanding and retracting the same, means carried by the lower end of said head for firmly holding said dogs in engagement with said reamer-body, and means carried by said head and engaging said reamer-body for normally holding said dogs in a retracted position during the passage of the underreamer through a casing.

6. In an underreamer, the combination of a reamer-body, laterally movable dogs carried thereby, a spring supported spreader head arranged between said dogs and slidably connected thereto for expanding and retracting said dogs, and means for holding said dogs in a retracted position during the passage of said underreamer through a casing.

7. In an underreamer, the combination of a reamer-body, laterally movable dogs connected thereto, a spreader head supported by said reamer-body for moving vertically between said dogs and expanding and retracting the same, means carried by the lower end of said spreader head for firmly holding said dogs in engagement with said reamer-body, and means carried by said head for

normally holding said dogs in a retracted position during the passage of said tool through a casing.

8. An underreamer comprising a reamer-body provided in its lower end with a groove, laterally-movable oppositely-disposed dogs movable horizontally in said groove, a spreader-head movable vertically between said dogs, means for normally holding said 10 spreader-head in engagement with said dogs, means carried by said spreader-head and engaging opposite sides of said reamer-body for holding said head in a lowered position during the passage of said underreamer 15 through a casing, and means carried by the spreader-head for engagement with the lower ends of the dogs when the latter are in an extended position to hold said dogs against vertical movement independently of the 20 reamer-body.

9. An underreamer comprising a reamer-body, laterally movable dogs connected thereto, said dogs movable horizontally towards and away from the axis of said body, a 25 spreader-head supported by said body and movable vertically between said dogs, means carried by said spreader-head and engaging said spreader-body for holding said head in a lowered position during the passage of the 30 underreamer through a casing, and resilient means carried by the spreader-head for engagement with the dogs when the latter are in an extended position to hold them against vertical movement independently of the 35 spreader-body.

10. An underreamer comprising a reamer-body, a pair of reamer-bits having a tongue and groove connection with the lower end of said body, a spreader-head having a tongue 40 and groove connection with said reamer-bits, said spreader-head movable vertically between the reamer-bits to extend and retract the same, and means carried by said spreader-head for engagement with the 45 reamer-bits when the latter are in an extended position to hold the same against vertical movement at their tongue and groove connection with the reamer-body.

11. An underreamer comprising a reamer-body, dogs slidably-connected to the lower 50 end thereof to move in a horizontal line towards and away from the axis of said body, means supported by said reamer-body for expanding and retracting said dogs, and

means for holding said dogs in a retracted 55 position during the passage of the tool through a casing.

12. In an underreamer, the combination of a reamer-body, reamer-bits carried thereby and having a sliding connection with the 60 body whereby they may be moved towards and away from the axis of said body, means operating between said reamer-bits and connected therewith for extending and retracting the bits, and resilient means carried by 65 the said first-named means for engagement with the reamer-bits when the latter are extended to force said reamer-bits towards the reamer-body and prevent lost motion at the point where said bits are connected to 70 said body.

13. In an underreamer, a reamer-body, reamer-bits having a tongue and groove connection with said body and movable laterally in a horizontal line towards and away 75 from the axis of said body, the said body having a recess at its lower end, a spreader-block movable vertically between the reamer-bits to extend and retract the latter, said spreader-block in the extended position of 80 the bits projecting into the recess in said body, and a spring-plate carried by the lower end of the spreader-head for engagement with the lower ends of the reamer-bits when the latter are in an extended position 85 to prevent lost motion between the bits and the reamer-body at the point where said bits are connected to said reamer-body.

14. An underreamer comprising a reamer-body, reamer-bits slidably connected to the 90 lower end thereof to move in a horizontal line towards and away from the axis of said body, means supported by said reamer body for extending and retracting said reamer-bits, means for holding said reamer-bits in 95 retracted position during the passage of the underreamer through a casing and a spring plate carried by the first-named means for engagement with the reamer-bits when the latter are in an extended position for forcing the reamer-bits towards the reamer-body, 100 as and for the purpose described.

In testimony whereof I affix my signature in the presence of two witnesses.
